STOPPER FOR BOTTLE

Franklin Douglas Northgrave, Arva, Ontario, and Samuel Joseph Cino, Hamilton, Ontario, Canada, assignors to London Winery Limited, London, Ontario, Canada

Filed Oct. 22, 1970, Ser. No. 25,601

Claims priority, application Canada Feb. 16, 1970

Term of patent 14 years

Int. Cl. D9—07

U.S. Cl. D9—285

FIG. 1 is an elevation view of a stopper for a bottle showing our new design;

FIG. 2 is a top plan view;

FIG. 3 is a bottom plan view thereof;

FIG. 4 is a section on the line IV—IV in FIG. 2; and FIG. 5 is a section on the line V—V in FIG. 5.

This is a continuation-in-part of design application Ser. No. 21,559, filed Feb. 16, 1970 and now abandoned.

We claim:

The ornamental design for a stopper for a bottle, as shown and described.
